(57) **CLAIM**

The ornamental design for a device for holding a bagel while being cut, as shown and described.

DESCRIPTION

FIG. 1 is a perspective view of a device for holding a bagel while being cut.

FIG. 2 is a left side elevational view thereof, the right side elevational view being a mirror image of the left side view.

FIG. 3 is a front elevational view thereof.

FIG. 4 is a rear elevational view thereof.

FIG. 5 is a top plan view of the device for holding a bagel while being cut; and,

FIG. 6 is a bottom plan view thereof.
